ADJUSTABLE PAINT BRUSH HOLDER
Gordon F. Lahive, 538 Cambourne W., Ferndale, Mich.
Filed Mar. 20, 1961, Ser. No. 96,835
1 Claim. (Cl. 211—65)

This invention relates to an adjustable paint brush holder which is adapted to be mounted on a leg of an artist's easel. More particularly, this invention relates to a paint brush holder having a horizontal support base adapted to be removably connected to a leg of an easel and a receptacle for paint brushes adjustably connected to the support base and movable relative to the support base throughout an angular range of approximately 180 degrees.

In the past, various paint brush holders for artists' easels have been proposed. However, such holders were generally fixed to the leg in one position. Since an artist utilizes various standing or sitting positions when painting, it was found that the prior art paint brush holders were either in the way or not readily accessible to the artist.

It is an object of the present invention to provide an adjustable paint brush holder which is especially adapted for storing an artist's paint brushes and which is adjustable for the convenience of the artist.

Another object of the present invention is to provide an adjustable paint brush holder which is adjustable throughout a substantial angular range so as to permit the artist to move the holder to a position which is readily accessible, depending upon the position of the artist while painting.

Still another object of the present invention is to provide an adjustable paint brush holder for an easel comprising a horizontal support base adapted to be connected to a leg of an easel and a conically shaped receptacle for paint brushes which is adjustably connected to the support base and movable relative thereto throughout a substantial angular range.

A further object of the present invention is to provide an adjustable paint brush holder having a horizontal support base adapted to be connected to a leg of an easel, a movable horizontal plate having an opening therein, adjustable fastening means connecting the plate to the base so as to permit angular motion between the plate and the base, and removable means on the plate for supporting a receptacle in said opening.

A still further object of the present invention is to provide an adjustable paint brush holder of the aforementioned type in which the support base is also adapted to carry a second receptacle which contains cleaning liquid for the paint brushes.

Another object of the present invention is to provide a novel and useful improvement in connecting the support base of the paint brush holder to the leg of the easel.

Still another object of the present invention is to provide an adjustable paint brush holder of the type described which is simple in construction, inexpensive to manufacture, easy to assemble and adjust, and which is also efficient and durable in use.

Other objects and features of the invention will become apparent as the description proceeds, especially when taken in conjunction with the accompanying drawings, illustrating preferred embodiments of the invention, wherein:

FIGURE 1 is a perspective view illustrating an adjustable paint brush holder mounted on a leg of an artist's easel.

FIGURE 2 is a plan view of the adjustable paint brush holder.

2

FIGURE 3 is an elevational view, partly in section, of the present invention.

FIGURE 4 is a modification of the present invention illustrating a novel manner of connecting the support base to the leg of the easel.

FIGURE 5 is a partial elevational view looking in the direction of arrows 5—5 of FIGURE 4.

FIGURE 1 illustrates an easel 10 having a plurality of legs 12 of substantially rectangular cross section. The easel 10 includes an artist's board 15 appropriately mounted a predetermined distance above the ground. On one of the legs 12 is mounted an adjustable paint brush holder represented by the numeral 14. The paint brush holder 14 may be mounted on the easel in one of two different ways, as is illustrated in FIGURE 3 and in FIGURES 4 and 5.

The adjustable paint brush holder 14 includes a substantially rectangular horizontal support base 16 which has a perpendicular flange 18 at one edge. The mounting leg 12 has a clip 20 which is appropriately connected to the leg by fastening means 22 including a bolt 23 and nut 24. After the flange 18 has been inserted behind the clip 20, the adjustment nut 24 is rotated in a direction so as to urge the clip 20 against the flange 18, thereby securing the support base 16 in a relatively fixed position. At the outer end of the support base 16 is provided a fixed pivot member or connector 26 which extends upwardly and is used for a purpose to be herein-after described. Mounted for angular rotation with reference to the support base 16 is a horizontal mounting plate 32 having a cylindrical opening 34 therein. The plate 32 is provided with an elongated longitudinally extending slot 36 which is adapted to receive the pivot member or connector 26. Adjustment of the plate 32 horizontally with reference to the support base 16 takes place by loosening a nut 30 threaded upon the connector 26, moving the plate 32 to the desired angular position, and tightening the nut 30.

A conically shaped receptacle 40 made from appropriate fabric material is supported by means of a removable annular ring 42 which is concentric with the opening 34 and is supported on the plate 32. The receptacle 40 has at the large open end thereof an outwardly turned annular flange 46 which is received in an annular groove 48 provided on the inner periphery of the ring 42. The ring 42 may be made from suitable material such as plastic and provides the necessary support for the receptacle 40. The ring 42 is removed along with the receptacle 40 by merely lifting the ring 42 and receptacle 40 from the cylindrical opening 34 provided in the mounting plate 32.

When in operation and it is required to change the position of the adjustable paint brush holder 14, all that is required is that the wing nut 30 be loosened and the plate 32 and paint brush receptacle 40 rotated to the proper location. As previously mentioned, the plate 32 is adjustable through a range of approximately 180 degrees.

It should be observed that the support base 16 has located near the mounting flange 18 another cylindrical opening as designated by the numeral 50. The opening 50 is smaller in diameter than the opening 34. The opening 50 is adapted to receive and support a removable cup 52 which contains liquid cleaning fluid for the paint brushes 54. The cup 52 also serves as an abutment for limiting the angular movement of the plate 32 in each direction to 90 degrees.

When the plate 32 and receptacle 40 are in the position illustrated in FIGURE 2, it should be observed that the perpendicular distances measured from the axis A—A to the side edges 54 and 56 of the plate 32 are equal, as

represented by the letter X. It should also be noted that in FIGURE 3 the distance between the center line of the connector 26 and the adjacent edge of the opening 50 is also equal to X.

From such a geometrical arrangement, it readily appears that the edges 54 and 56 will strike the cup 52 when the plate is rotated toward one of its extremities.

If the cup 52 was not utilized, then the plate 32 and receptacle 40 could be moved through a substantially greater angle than 180 degrees.

FIGURES 4 and 5 show another embodiment of the present invention. When a cylindrical leg 60 of an easel is utilized, the support base 16 may be mounted somewhat differently as is illustrated. The same support base 16 and plate 32 are utilized. However, the base and plate assembly is inverted so that the flange 18 extends upwardly rather than downwardly as in the previous embodiment. With such an arrangement, the annular ring 42 is supported by the side of the plate 32 opposite the side illustrated in FIGURE 3.

An expandable clamp 62 including elongated arms 64 and 66 is adapted to extend partly around the leg 60, as is best illustrated in FIGURE 4. Arms 64 and 66 are provided with aligned holes for receiving a threaded connector 68 which extends therethrough and through an opening provided in the flange 18. A wing nut 70 is threaded on the outer end of the threaded connector 68 and is adapted to be rotated in a manner so as to fasten the flange 18 and arms 64 and 66 together.

The support base 16 and plate 32 may be made from steel or from a plastic material. Alternatively, the base 16 and plate 32 could be made from steel wire so as to provide the necessary adjustable support for the receptacle 40. The conically shaped fabric bag or receptacle 40 is made from cloth. The conical shape of the bag 40 is important since it permits the paint brushes 54 to separate from each other, as illustrated in FIGURE 3.

From such a construction, it appears that the bag 40 can be easily removed from its support and collapsed for storing or shipping along with the base 16 and plate 32.

The drawings and the foregoing specification constitute a description of the improved adjustable paint brush holder in such full, clear, concise and exact terms as to enable any person skilled in the art to practice the invention, the scope of which is indicated by the appended claim.

I claim:

An adjustable paint brush holder comprising a substantially horizontal elongated base having a substantially perpendicular flange at one end attachable to an upright leg of a painter's easel and having adjacent the other end thereof an upstanding fixed elongated threaded pivot member, a substantially flat and horizontal elongated mounting plate having the back end portion disposed in

surface to surface relation with said other end of said base and having in said back end portion a longitudinally extending elongated slot arranged on the longitudinal axis of said mounting plate and receiving said upstanding pivot member whereby said mounting plate may be adjusted horizontally about said pivot member, said mounting plate being provided at the other end thereof with a relatively large circular opening, the sides of said mounting plate tapering inwardly and rearwardly from a point opposite said opening to the end thereof overlying said other end of the base, a removable annular ring resting upon said mounting plate in surface to surface contact therewith, said ring surrounding and being concentric with said opening, an upwardly opening conically shaped paint brush receptacle made from fabric in said opening and supported entirely by said removable annular ring, said base being provided between said pivot member and said flange with a centrally located circular opening which is substantially smaller than said first-mentioned opening, the closest distance between the axis of said pivot member and said last-mentioned circular opening being equal to approximately one-half the total distance between the sides of said mounting plate measured along a line passing through the axis of said pivot member and perpendicular to the longitudinal axis of said mounting plate, a removable cup in said last mentioned opening and including portions which extend above and below said base, the portion of said cup above said base being operable as a stop abutment for limiting horizontal angular adjustment of said mounting plate with respect to said base to approximately 180°, and means engaging said pivot member for holding said mounting plate in adjusted position, said means comprising a nut threadedly engaging said pivot member and frictionally engaging said mounting plate.
